E. TROYE,
METHOD OF PREVENTING PUNCTURES IN ELECTRIC FLAME ARC FURNACES,

UNITED STATES PATENT OFFICE.

EINAR TROYE, OF CHRISTIANIA, NORWAY, ASSIGNOR TO NOESK HYDRO-ELEKTRISK KVAELSTOFAKTIESELSKAB, OF CHRISTIANIA, NORWAY.

METHOD OF PREVENTING PUNCTURES IN ELECTRIC FLAME-ARC FURNACES.

1,148,343.

Specification of Letters Patent. Patented July 27, 1915.

Application filed August 13, 1914. Serial No. 856,600.

To all whom it may concern:

Be it known that I, EINAR TROYE, a subject of the King of Norway, residing at Solligaten 7, Christiania, Norway, have invented certain new and useful Improvements in Methods of Preventing Punctures in Electric Flame-Arc Furnaces; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention has for its object a method of preventing punctures in electric flame arc furnaces.

In electric flame arc furnaces owing to the high temperatures and the high working tensions generally used there is always danger of puncturing through the brick wall to the outer cover (the iron mantle), particularly when the same is connected to earth for the sake of safety. It has been tried to reduce this danger by making the lining of the furnace or the brick wall with ample dimensions. But hereby many inconveniences and increased expenses are caused, without the purpose being attained with any certainty.

The applicant has now found, that it is possible to reduce the thickness of the brick wall in a considerable degree and to obtain completely puncturefree furnaces by arranging between the brick wall and the wall of the furnace (in the following indicated as the cover of the furnace) one or more air spaces, through which may flow comparatively cold air, for instance a part of or the whole quantity of air, which is to be treated in the furnace. If the furnace is made for supplying gases of different composition or temperature it may be desirable or necessary to undertake a corresponding division of the insulating air space. The insulation will of course be best, if the air space is put under pressure or if a plurality of air spaces is arranged outside of one an-

other, viz. by inserted detached walls of asbestos or the like.

By this method the applicant has as mentioned obtained completely punctureless furnaces, a result which has not been possible by the use of compact brickwork. It has also been proved, that the walls are spared in a considerable degree, because the temperature in the brick wall is more uniform. At the same time higher temperatures, smaller dimensions and a smaller flame space can be maintained and an improvement in the yield is attained, by the fact that the current loss in the earth is avoided.

The invention is illustrated in the accompanying drawing by a vertical section through a furnace in which—

1 indicates the iron mantle, 2 the brick wall of the furnace, 3 the air supply apertures and 4 the space between mantle and wall; 5 are the electrodes.

Claims:

1. The method of preventing punctures in electric flame arc furnaces, which consists in conducting gas or air streams of a suitable temperature and pressure between the furnace wall or lining and the cover of the furnaces.

2. The method of preventing punctures in electric flame arc furnaces, which consists in conducting gas or air streams of a suitable temperature and pressure between the furnace wall or lining and the cover of the furnaces the insulating layers of air consisting partly or completely of the air or gas, which is to be conducted into the furnace for treatment.

3. The method of preventing punctures in electric flame arc furnaces, which comprises conducting air or gas streams at a suitable temperature and pressure between the furnace wall or lining and the cover of the furnace, and causing said air or gas to thence pass into the furnace chamber at various parts of said chamber.

4. The method of preventing punctures in electric flame arc furnaces, which comprises conducting air or gas streams at a suitable

temperature and pressure from opposite sides of the furnace to the space between the furnace wall or lining and the cover of the furnace, and causing said air or gas to enter the furnace chamber in jets distributed over said opposite sides.

In testimony that I claim the foregoing

as my invention, I have signed my name in presence of two subscribing witnesses.

EINAR TROYE
